UNITED STATES PATENT OFFICE

132,129

DESIGN FOR A BROOCH

Helen C. Maloney, Green Bay, Wis.

Application January 7, 1942, Serial No. 105,045

Term of patent 3½ years

To all whom it may concern:

Be it known that I, Helen C. Maloney, a citizen of the United States, residing in Green Bay, in the county of Brown and State of Wisconsin, have invented a new, original, and ornamental Design for a Brooch, of which the following is a specification, reference being had to the accompanying drawing, forming a part thereof, and in which

Fig. 1 is a front view of a brooch embodying my new design;

Fig. 2 a top plan view of the same; and

Fig. 3 a side view of the same.

I claim:

The ornamental design for a brooch, as shown.

HELEN C. MALONEY.
